Atty.

UNITED STATES PATENT OFFICE.

DUDLEY D. GRAY, OF LAKEWOOD, OHIO.

SUPPORT FOR COMPUTING MACHINES.

Application filed September 2, 1925. Serial No. 54,165.

The operation of a certain class of computing machines, when the machines are placed upon desks or tables of average height, proves very tiring to the operator because of the strained position in which he is required to hold his arm and hand while manipulating the keys; and the angle of vision is such that difficulty is experienced in seeing the characters on the keys. These circumstances 5 reduce the efficiency of the operator and depreciate the character or accuracy of the work.

Special desks are made for supporting computing machines at a convenient elevation, but these are relatively expensive, and they occupy floor space which usually can be employed to better advantage. On account of these facts, the special desks are used comparatively little.

20 It is the primary purpose of my invention to provide means, preferably in the nature of an attachment, for supporting computing machines at the required angle of inclination to afford the operator the greatest convenience and comfort.

Further objects of the invention are to provide a very simple and inexpensive attachment that may be quickly and very easily secured to a computing machine without the 30 use of screws or other fastening devices and without the need of tools of any kind; that may be adjusted to support the machine at different angles; that serves to support the machine with a slight degree of resiliency so 35 as to absorb shocks incident to the striking of the keys; and that involves simple and cheap means for adjusting the length of either leg of the attachment to compensate for any slight irregularities arising in the 40 manufacture of the device.

The foregoing objects, with others herein-after appearing, are attained in the embodiment of the invention illustrated in the accompanying drawing wherein Fig. 1 is a perspective view of the attachment showing it as applied to a computing machine (illustrated conventionally by dotted lines); Fig. 2 is a side elevation of a computing machine equipped with the attachment, different 45 angles of inclination at which the machine may be supported being indicated by the dotted line positions of the machine and attachment; and Fig. 3 is a central vertical section through the attachment, showing it as applied to a computing machine that is indicated by dotted lines.

The attachment comprises a saddle 1 that is preferably made of a rectangular plate of resilient sheet metal. The plate is formed at its ends to provide grips 2, and the central portion of the plate is depressed somewhat with respect to the portions adjacent the grips 2, as clearly shown in Figs. 1 and 3. Adjacent the ends of the depressed portions, the plate is punched to provide openings within which the ends of tubular legs 3 are swaged, the legs having circumferential beads 4 against which the plate 1 is engaged, the ends of the legs beyond said plate being flanged outwardly by a suitable swaging tool 70 or die. Feet or pads 6, of rubber or other similar material, having relatively deep sockets, are applied to the legs.

Should it be found, when the parts are made and assembled, that one of the legs is 75 slightly shorter than the other, one or more of the slugs, struck from the plates 1 to provide apertures for the legs 3, may be placed within the bottom of the socket of the foot or pad 6 which is applied to the shorter leg. 80 The right hand leg of the attachment (as it is viewed in Fig. 3) is shown as lengthened by the use of one such shim or slug 8.

The normal transverse curvature of the saddle 1 is such as will bring the grips considerably closer together than the width of the base flange 9 of the computing machine 85 10. When it is desired to apply the attachment to a machine, the outer ends of the legs 3 are pressed toward each other which causes the saddle 1 to be straightened out more or less, increasing the distance between the grips 2 sufficiently to allow the attachment to be slipped over the base flange 9. Upon releasing the legs, the saddle contracts and clamps 90 95 itself firmly to the machine.

The attachment may be adjusted longitudinally of the machine until the desired inclination of the machine is effected. This inclination should be such that the plane of 100 the bank of keys is approximately parallel to the angle of the forearm of the operator, as illustrated in Fig. 2.

Having thus described my invention, what I claim is:

1. An attachment for computing machines comprising a saddle of resilient sheet metal having grips at its opposite ends for cooperation with the base of the computing machine, said plate being curved from end to end, and 110 legs depending from said plate adjacent the ends thereof.

2. An attachment for computing machines comprising a saddle of resilient sheet metal having grips at its opposite ends, said saddle being curved from end to end and provided adjacent its ends with apertures, and legs having holding means engaged through said apertures.

3. An attachment for computing machines comprising a saddle of resilient sheet metal having grips at its opposite ends, said saddle being curved from end to end and provided adjacent its ends with leg receiving apertures, tubular legs having their upper ends swaged within said apertures, and pads applied to the lower ends of said legs.

4. An attachment for computing machines comprising a saddle of resilient sheet metal having grips at its opposite ends, said saddle being curved from end to end and provided adjacent its ends with leg receiving apertures, tubular legs having their upper ends swaged within said apertures, and socketed pads of suitable material for application to the ends of the legs.

5. An attachment for computing machines

comprising a saddle of sheet metal having means for attaching it to the machine, said saddle being provided adjacent its ends with leg receiving apertures, legs having attaching means engaged through said apertures, 30 socketed pads of suitable material applied to the ends of the legs, and a shim within the socket of one of the pads between the end of the corresponding leg and the bottom of the socket.

6. An attachment for computing machines comprising a saddle of resilient sheet metal having grips at its opposite ends, said saddle being curved from end to end and provided adjacent its ends with leg receiving apertures, 40 tubular legs having their upper ends swaged within said apertures, socketed pads of suitable material for application to the ends of the legs, and a shim within the socket of one of the pads between the end of the corresponding leg and the bottom of the socket.

In testimony whereof, I hereunto affix my signature.

DUDLEY D. GRAY.
